ATTORNEY.

Geo. F. Kimmel.

Patented Dec. 28, 1926.

UNITED STATES PATENT OFFICE.

EARNEST F. THORP, OF BONO, ARKANSAS.

RAIL CLAMP.

Application filed July 22, 1925. Serial No. 45,431.

My invention relates to improvements in rail clamps for use in connection with the track rails of railway tracks; and the object thereof is to provide, in a manner as herein-
 5 after set forth, a track rail clamp to prevent the rails of a railway track from spreading and for holding the rails of the track in gauge thereby reducing the possibility of accidents, due to spreading rails, to a mini-
 10 mum.

Further objects of the invention are to provide, in a manner as hereinafter set forth, a rail clamp which is comparatively simple in its construction and arrangement, strong, durable, acting not only as a means to prevent the spreading of the rails but as a bracing device therefor, thoroughly efficient in its use, conveniently installed with respect to the rails of a railway track, and compara-
 15 tively inexpensive to manufacture.

With the foregoing and other objects in view, the invention consists of the novel construction, combination and arrangement of parts as hereinafter more specifically de-
 20 scribed and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:

Figure 1 is a cross sectional view of a railway track, showing the adaptation thereto of a rail clamp in accordance with this invention.

Figure 2 is a fragmentary view in top plan of a railway track, showing the adaptation thereto of a rail clamp in accordance with this invention.

Figure 3 is a side view of the combined holder, guide and abutment element.

Figure 4 is a top plan view of a combined brace and clamping member.

Figure 5 is a side view of a combined brace and clamping member.

Figure 6 is a top plan view of the upper brace member.

Referring to the drawings in detail 1 and 2 indicate the rails of a track and which are mounted upon ties 3. The rails 1 and 2 are fixedly secured to the ties by spikes 4.

A rail clamp in accordance with this invention is arranged between a pair of ties 3 and is disposed transversely with respect to the

track. The rail clamp includes a pair of oppositely disposed combined brace and clamping members referred to generally by the reference characters 5, 6, a pair of upper brace members referred to generally by the reference character 7, 8 a combined holder, guide and abutment element or member referred to generally by the reference character 9, a turn buckle 10, a pair of clamping nuts 11 associated with the member 5, a pair of clamping nuts 12 associated with the member 6, a connecting device 13 between the members 5 and 7 and a connecting device 14 between the members 6 and 8.

The combined brace and clamping members are oppositely disposed with respect to each other, and as they are of the same construction, but one will be described, as the description of one will apply to the other. With reference to Figures 4 and 5, each combined brace and clamping member, comprises a flat bar 14 of substantial length having a tapered rear portion 15 which merges into a peripherally threaded cylindrical shank 16 arranged at the inner end of the combined brace and clamping member. The outer end of the bar 14 terminates in an overhanging clamping head 17 which extends inwardly with respect to the bar 14 and is spaced therefrom as at 18 to provide a pocket. The top of the head 17 is formed with a seat 19 and a shoulder 20. The track rail is mounted upon the outer end of the bar 14 and the outer side of the base 21 thereof is extended into the pocket 18. The inner side of the head abuts against the outer face of the web 22 of the track rail and the seat 19 of the head 17 is positioned against the outer side of the lower face of the ball or head 23 of the track rail. The shoulder 20 abuts against the outer side edge of the head or ball 23 of the track rail. The bar 14 is formed in proximity to the tapered portion 15 of the combined brace and clamping member with a lengthwise extending slot 24.

As the upper brace members 7 and 8 are of like construction, but one will be described, as the description of one will apply to the other. The upper brace members are oppositely disposed with respect to each other and each consists of a bar 25, having the major portion of its length flat and square in cross section. The outer end terminal portion of the bar 29 is disposed at an upward inclination, as indicated at 26 and which is adapted to abut against the inner face of the web 22.

of the track rail and seat upon the upper face of the inner side of the base 21 of the track rail. The inner end of the bar 25, centrally thereof, is formed with a polygonal shaped lug 27 for a purpose to be presently referred to. The bar 25 intermediate its ends is formed with a lengthwise extending slot 28, which when the bar is in bracing position, is arranged in alinement with the slot 24 of a combined brace and clamping member. The combined holder, guide and abutment member or element is of U-shaped contour and it includes a base 29, a pair of upstanding arms 30, 31. Each of said arms is formed near its lower end with an opening 32 and on its outer face in proximity to its upper end with a pocket 33. Each arm at its upper end is formed with a right angularly disposed flange 34. When the rail clamp is mounted in coupling position, as well as bracing position, with respect to the track rails 1 and 2, the combined bracing and clamping members 5, 6 are arranged to extend in opposite directions and with the shanks 16 thereof extended through the openings 32 formed in the arms 30, 31. The clamping heads 17 are positioned against and exteriorly with respect to the track rails 1 and 2. The element 9 is arranged centrally of the track bed and after the shanks 16 have been extended therethrough into the turn-buckle, the latter is adjusted so that the heads 17 of the members 5, 6 will be tightly clamped against the track rails 1 and 2. After the members 5 and 6 have been set in the desired position, the pairs of clamping nuts 11, 12 are adjusted so that one of each pair will abut against the inner face of an arm of the member 9, see Figure 1. Before the members 5 and 6 are tightly clamped in position, the upper brace members 7 and 8 are arranged in superposed relation with respect to the members 5, 6, the lugs 27 are mounted in the pockets 33 and the inclined outer ends of the members 7 and 8 are positioned against the webs of the track rails. The members 5, 6, 7 and 8 are then tightly clamped against the track rails and the members 7 and 8 brought in tight abutting engagement with the arms of the member 9. After the parts are in the position as shown, the connecting devices 13 and 14, each of which consists of a headed bolt and a nut, are extended through the alining slots 24, 28 and the members 5 and 6 are tightly

connected to the braces 7 and 8. The slots 24 and 28 provide for adjustment when desired, to enable the connecting device to be mounted in position.

It is thought that the many advantages of a rail clamp, in accordance with this invention and for the purpose set forth, can be readily understood, and although the preferred embodiment of the invention is as illustrated and described, yet it is to be understood that changes in the details of construction can be had which will fall within the scope of the invention as claimed.

What I claim is:—

1. A rail clamp comprising a combined holder, guide and abutment member of U-shaped contour, a pair of oppositely disposed combined brace and clamping members adapted to be held in clamping engagement with respect to a pair of track rails and having their inner ends extending through the arms of said abutment member, a pair of oppositely disposed upper braces for interposition between said abutment member and the pair of track rails, and means engaging with the inner ends of said brace members, within said abutment member, for maintaining said brace members in clamping engagement with the track rails and further for maintaining said braces in abutting position with respect to the track rails and said abutment member.

2. A rail clamp according to claim 1 having the inner ends of the upper braces provided with means for seating in the arms of said abutment member.

3. A rail clamp according to claim 1 having a pair of connecting devices, one of the connecting devices connecting an upper brace to a combined brace and clamping member and the other of said connecting devices connecting the other upper brace to the other combined brace and clamping member, said braces and combined brace and clamping members provided with registering slots for the passage of said connecting devices.

4. A rail clamp according to claim 1 having the inner ends of said upper braces provided with means for seating in the arms of said abutment member, and with the arms of said abutment member provided with means for overlapping the top of the upper braces at the inner ends thereof.

EARNEST F. THORP.
